UNITED STATES PATENT OFFICE.

WALTER PRESTON HENDON, OF DALLAS, TEXAS.

DESIGN FOR A PLOW-BEAM FOR DISK PLOWS.

SPECIFICATION forming part of Design No. 33,114, dated August 21, 1900.

Application filed May 17, 1900. Serial No. 17,072. Term of patent 14 years.

all whom it may concern:

Be it known that I, WALTER PRESTON HENDON, a citizen of the United States, and a resident of the city of Dallas, county of Dallas, and State of Texas, have invented and produced a new and original Design for Plow-Beams for Disk Plows, of which the following is a specification, reference being had to the accompanying drawings, forming part thereof.

Figure 1 is a plan view of a plow-beam embodying my design. Fig. 2 is an elevation of one side of the beam shown in Fig. 1, and Fig. 3 is an elevation of the other side of the beam.

As shown in the drawings, the beam is in the form of an open frame having substantially-parallel members A and B, having between them, at their forward ends, a spacing block or piece C. At their rear end portions

the members A and B extend at an angle to 20 the main portion, as indicated at A' B', and between these end portions A' and B' is a bracket D of the configuration shown in the drawings.

The essential feature of the design is the 25 open frame having the substantially-parallel members provided with angular rear portions between which is a bracket.

Having described my invention, what I claim as new, and desire to secure by Letters 30 Patent, is—

The design for a plow-beam for disk plows as herein shown and described.

WALTER PRESTON HENDON.
